UNITED STATES PATENT OFFICE

HANS DEUTSCH, OF VIENNA, AUSTRIA, ASSIGNOR TO THE FIRM ALEX FRIEDMANN, OF VIENNA, AUSTRIA

PREHEATER OR ECONOMIZER FOR LOCOMOTIVES

Application filed February 28, 1929, Serial No. 343,420, and in Austria March 10, 1928.

My invention relates to locomotive pre-heaters or economizers of the type heated by the exhaust steam of the locomotives and comprising a hot water tank within which hot water may be stored or accumulated and afterwards fed into the boiler to reduce the consumption of fuel. Such reduction of the fuel consumption which may be obtained by using pre-heaters or economizers heated by the exhaust steam of locomotives depends upon the relation between the period of time during which the regulator of the locomotive is open and during which therefore exhaust steam is available for heating the feed water and the entire service period during which the locomotive is under steam. Therefore it is a well known fact that the reduction of the fuel consumption obtained by the use of pre-heaters or economizers is larger in express trains, the locomotives of which are running with open regulator during a comparatively long time while stops occur only at rare intervals and for short periods, but is materially smaller in slow trains in which the stops are more frequent and more extended.

The amount of reduction of the fuel consumption depends, however, also on the way in which the feeding device of the boiler is manipulated and mainly on whether or not the feeding device of the boiler is operated exclusively or mainly while the regulator of the locomotive is open.

The driver of an engine has always the tendency to refrain from using the feeding device of the boiler during the period within which the regulator is open because he does not like to lower the steam pressure within the boiler by the introduction of comparatively cold water, just during the period within which the cylinders of the engine are consuming steam.

From the point of view of the driver therefore the most favourable moment for the feeding of the boiler is the moment just after the shutting of the regulator and this is actually the moment at which the driver will generally actuate the feeding device of the boiler. In this moment the steam pressure within the boiler is markedly raising because the

consumption of steam in the engine has been suddenly interrupted and on the other hand the introduction of comparatively cold feed water will prevent effectively such raising of the steam pressure within the boiler.

This way of manipulating the feeding device, generally used by the engine drivers, has, however, the consequence that the reduction of fuel consumption that can be actually derived from the introduction of a pre-heater or economizer heated by exhaust steam is by far smaller than the theoretical amount of reduction of fuel consumption that seems to be possible.

Now my invention has for its object to provide an arrangement wherein both these requirements, which are at variance with each other, may be fulfilled in spite of their seeming conflict. The requirement to feed when the regulator is open in order to be able to utilize a pre-heater or economizer heated by exhaust steam, can be brought into agreement with the other requirement to feed mainly when the regulator has been shut in order to maintain the boiler pressure at the required value, by providing a hot water tank or container which is fed with a mixture of water and exhaust steam when the regulator is open.

In order to distinguish my invention from the prior art it may be mentioned that it has already been proposed to use arrangements in which hot water is stored within a tank or container, the latter being, however, arranged in such a way that the hot water is delivered from it also during the period within which the regulator is open and consequently during which exhaust steam is available. With these arrangements, however, bearing in mind the driver's aversion against feeding during the opening of the regulator it happens in most cases in which the regulator is kept open for a protracted period of time that it will be necessary to feed the boiler before the shutting of the regulator on account of the rapid falling of the water level within the boiler. In arrangements of this kind therefore a very large amount of hot water is already consumed within the period in which the

regulator is open, so that only part of the volume of the hot water tank or container is filled with hot water and therefore actually operative for the feeding during the 5 period when the regulator has been shut. Owing to the restricted space available on a locomotive the entire volume of the hot water tank is necessarily limited so that it can be conveniently mounted on the locomotive. According to my invention, however, the volume of the hot water tank may be utilized to its full extent as a storage means for hot water in the proper sense of the word, as no water can be drawn from it 10 while the regulator is closed.

To secure this object in an embodiment of my invention a hot water tank or container is arranged on the locomotive in addition to the usual feeding device with pre-heater and from the outlet pipe of the usual feeding device there branches off a pipe leading to the storage tank or container which may be shut if necessary.

On account of the high temperature of the 25 stored hot water and in order to diminish unnecessary losses of heat the feeding path for the hot feed water of the boiler is not the same as that of the cold water of the tender, but according to my invention and 30 in contradistinction to former proposals a separate path is provided for the hot water, which is led to the boiler on the shortest possible way.

If now the boiler is to be fed while the 35 regulator is open the passage leading to the hot water storage tank or container is to be closed and the feeding device is to be operated in the usual manner. If, however, the feeding of the boiler is to be interrupted 40 while the regulator is open, the path of the water under pressure leading to the boiler is to be shut and the passage leading to the hot water container or storage tank is to be opened. If the regulator is now shut the 45 stored hot water can be carried from the container into the boiler.

The arrangement according to my invention is also distinguished from other arrangements hitherto known by the fact that 50 for feeding hot water from a storage tank or container into the boiler the delivery pipe from the container is not connected with the suction pipe of the cold water pump, as usual, because in this case the hot water would 55 have to pass over a too long way before entering into the boiler so that it would be subject to a very remarkable cooling, but, according to my invention the hot water is brought into the boiler on the shortest possible way and is not only thus protected 60 against cooling but is even heated further by mixing it with live steam.

My invention is illustrated in the accompanying drawing by way of example and the 65 embodiment illustrated therein shows an

arrangement with a cold water feeding path leading into the boiler over an exhaust steam injector, while a second feeding path leads from the hot water storage tank or container into the boiler, the preferred arrangement such as illustrated showing a hot water storage tank arranged above the water level of the boiler, whereby the water may flow into the boiler by gravity so that a separate pump or injecting device for such 75 water becomes unnecessary.

Fig. 1 shows this arrangement in use on a locomotive while Fig. 2 is a section through the controlling mechanism and distributing apparatus arranged within the 80 driver's cab and also through the exhaust steam injector used.

Referring to Fig. 1 of the accompanying drawing 1 designates the exhaust steam injector, 2 the pipe for feeding water from the tender to the injector, 3 the exhaust steam pipe, 4 a live steam pipe which carries steam of boiler pressure to the live steam nozzle of the injector; 5 is a delivery pipe which is capable of carrying the heated feed 90 water according to requirements either into the pressure pipe 7 leading into the boiler over the feed valve 6 or into the pipe 9 leading to the hot water storage tank or container 8.

The injector, as will be seen from Fig. 2, is in general of any approved type and comprises a live steam nozzle 21, an exhaust steam nozzle 22, a combining or mixing nozzle 23 and a delivery nozzle 24. The water 100 is fed through the tube 2 and passes a water admission valve 19 controlled in a manner hereinafter described. Besides an overflow pipe or opening 10 leads to the overflow chamber of the injector as usual.

The controlling and distributing apparatus 15 is arranged in the engine driver's cab, is for controlling the various steam and water paths leading to and from the injector, the boiler and the hot water tank and is connected with a pipe 11 carrying live steam from the boiler to the master valve 35. A pipe 12 is arranged for the purpose of transmitting the pressure of the steam chest of the engine cylinders or of the main steam pipe leading thereto to certain spaces or chambers in the controlling and distributing apparatus 15 hereinafter to be described and to the injector. This pipe has two branches 13 and 14 leading to the apparatus 15 and 110 to the injector respectively. A pipe 16 connects the hot water storage tank or container to the boiler and a non-return valve 17 opening only on the boiler side is inserted in said connection.

Moreover a live steam pipe 18 is provided which connects the apparatus 15 in the engine driver's cab with the said container 8. The water valve 19 of the injector which is capable of checking the flow of water from 130

the tender to the injector when the master valve 35 is closed is operated by a valve or piston 20 which is connected with the pipe 14 and is capable of opening said water admission valve when steam of boiler pressure is admitted to the pipe 14.

The apparatus 15 is arranged within the driver's cab and is actuated by means of a hand operated master valve 35, carrying two valve disks. One of said valves is the steam admission valve 25 which according to its position opens or closes a passage through which steam of boiler pressure may be admitted into a space 26 within which also an automatically or steam operated counter valve 27 is arranged.

The counter valve 27 is a two seat valve with an upper seat and a lower seat and it controls two valve openings 28 and 29. The upper opening 28 controls the steam path through pipe 4 which leads to the live steam nozzle 21 of the injector while the lower opening 29 of the valve controls the path through pipe 18 leading to the hot water container. The counter valve 27 is moreover provided with a projecting steam carrying a kind of piston 30 which works within a casing forming a guide but which is not made tightly fitting within said guide.

Above said piston 30 a non-return valve 31 is arranged, capable of being lifted by said double seat valve or by a process on its piston under certain conditions. Below the double seated counter valve 27 a further valve 32 is arranged which throttles the steam entering that may happen to be discharged from the hot water tank or container through the pipe 18 into the space 26. Said valve is freely movable within its casing and when steam flows from the hot water tank or container to the space 26 it is in its upper position of rest in which it will shut off the passage 29 so that an exit of steam can take place only through small ports or openings 33 provided in the valve body. If, however, the valve 25 is open and steam flows into the space 26 and into the pipe 18 the valve 32 is in its lower position of rest in which free passage of steam to said pipe 18 is allowed. The master valve 35 besides carrying the valve disk 25 also carries a further valve disk 34 which is closed when valve disk 25 is opened and vice versa and which when closed will shut the steam path 9 leading to the container.

The operation of this arrangement is as follows:

When the regulator of the locomotive is opened exhaust steam from the engine will flow through the pipe 3 to the injector 1. At this moment the steam chest or the main steam pipe leading thereto is under steam pressure and therefore also the pipes 12, 13, 14 are carrying steam pressure. The valve or piston 20 controlling the water admission

of the injector is therefore shifted into its position on the right side and prevents the flowing of steam from the pipe 14 into the injector but holds the water admission valve 19 of the injector in its open position whereby water from the tender may flow to the injector 1 through the pipe 2. The mixture of water from the tender entering into the injector and of exhaust steam supplied through pipe 3 to the nozzle 22 is able as well known by virtue of the condensation of the exhaust steam and by suitable acceleration of the velocity of the mixture in the nozzles of the injector to overcome a counterpressure up to approximately 10 metric atmospheres.

It is now assumed that a phase of operation is under consideration during which it is not possible to feed the boiler. Therefore the master valve 35 and the steam admission valve disk 25 is closed while as described the valve 34 is open and thus opening the path through pipe 9 to the hot water container 8. As the hot water tank or container 8 is for the moment pressureless the water will flow from the pipe 5 into the pipe 9 and to the hot water tank or container 8 as of course it will follow the path that presents the least resistance, the other path 7 into which pipe 5 discharges leading to the boiler 95 with its heavy counterpressure.

If now the driver wishes to feed the boiler while the regulator is still open he will actuate the master valve 35 and the valve 25 will be opened so that steam from the boiler can now enter through pipe 11 and will penetrate into the space 26. The double seated counter valve 27 which is now in its lower position of rest is held in this position by the steam pressing on its upper surface and the steam is entering through the upper opening 28 of the valve 27 into the pipe 4 and from thence is led to the live steam nozzle 21 of the injector. The live steam jet now further accelerates the mixture of exhaust steam and water flowing through the injector and therefore enables that mixture to overcome the counterpressure of the boiler. The water thus flows with a higher velocity through the pipe 5 and as the valve disk 34 has closed its opening, when the master valve 35 was actuated, so that the path to the hot water tank or container 8 is no longer open the water under pressure now flows through the pipe 7, passes the feed valve 6 and flows into the boiler.

When the feeding of the boiler is interrupted the master valve 35 is closed, whereby the admission of live steam through the pipe 4 flowing to the live steam nozzle 21 is interrupted while on the other hand the valve 34 is opened and the feeding of water to the hot water container is continued in the manner above described.

If the regulator of the locomotive is now

closed the flowing of exhaust steam through the pipe 3 ceases and the pressure in the pipes 12, 13, 14 which are connected with the steam chest or with the main steam pipe leading 5 thereto will also disappear. Therefore the water admission valve 19 is closed partly by the flow of water and partly by a spring which presses upon it.

If water is now to be fed into the boiler 10 the master valve 35 with the admission valve 25 is again opened. The steam admitted to the space 26 and flowing through the upper valve opening 28 by its pressure on the piston like disk 30 lifts the counter valve 27 be- 15 cause no pressure is now acting on the non-return valve 31, the pipes 12, 13, 14 being pressureless. As soon as the counter valve 27 has come to its upper position of rest it 20 will be held in said position by the steam pressure and the live steam will now flow through the lower valve opening 29 into the pipe 18, and will then flow to the hot water tank or container 8. As a connection between 25 the steam space of the boiler and the hot water tank or container 8 is thus established the said hot water tank or container 8 will now be set under boiler pressure and the hot water contained therein will now flow into the boiler by virtue of its own gravity, when 30 the said tank or container is arranged at a higher level than the water level as shown in the drawing.

To interrupt the discharge of water from 35 the hot water tank or container 8 into the boiler it is only necessary to shut the master valve 35. If now the regulator is again opened whereby steam is again admitted to the pipe 3 and whereby the pipes 12, 13, 14 are again coming under pressure and the 40 water admission to the injector is re-opened the mixture of exhaust steam and water is now no longer able to enter of its own accord into the pipe 5 as this pipe is connected to the pipe 9 in which the same pressure will pre- 45 vail as in the hot water tank or container 8 which is still under boiler pressure. As how- 50 ever by opening the regulator the non-re- turn valve 31 had been pressed upon its seat the counter valve 27 is now lifted from its upper seat and the steam within the hot 55 water tank or container 8 now enters into the pipe 18 and passes through the ports or open- 60 ings 33 which are throttling the steam into the space 26 and into the pipe 4. It will thus 65 finally reach the live steam nozzle 21 where it will accelerate in the manner described the mixture of exhaust steam and water so that said mixture is capable to overcome the counterpressure and to enter into the pipe 5 and to flow through the open valve 34 into the hot water tank or container.

The provision of the throttling ports or 65 openings 33 has to effect that the counter valve 27 by the steam flowing from the hot water tank or container 8 through the pipe

18 to the path 26 is lifted only to such an extent that said valve rests upon the non-re- 70 turn valve 31 while said non-return valve 31 itself can not be opened thereby as it would be the case especially when the admission of steam to the cylinders would be throttled while no throttling would occur within the ports 33. By thus opening the non-return valve 31 the counter valve 27 would come to its upper position of rest thus closing the 75 opening 28 and would prevent the admission of the steam from the hot water tank or container 8 into the pipe 4.

The invention can of course also be car- 80 ried into effect by other co-operating ele- 85 ments than those shown in the drawing which illustrates the preferred form only and especially it is also applicable in cases where the hot water container is arranged at a lower level than that of the boiler. In this case only a pump or injector or any other appa- 90 ratus capable of lifting the water from the lower level to the higher level of the boiler has to be inserted, which is operated by hand or in a like manner as that described and 95 which allows to overcome the difference be- 100 tween the levels.

What I claim is:—

1. An arrangement for supplying feed wa- 95 ter to locomotive boilers, comprising a hot water storage tank, a cold water tank, a dis- 100 tinct and separate feeding path leading re- 105 spectively from each of said tanks to the boiler, a feeding device which when supplied with live steam feeds the water from the hot 110 water storage tank over one of the said feed- 115 ing paths into the boiler, a second feeding device which when supplied with live steam feeds the water from the cold water tank over the second of said feeding paths into 120 the boiler, and members controlled automatic- 125 ally by the pressure in the valve chest of the engine which depends from the position of the locomotive regulator, said members controlling the admission of live steam to 130 said feeding devices, live steam being ad- 135 mitted to the first named feeding device only when the locomotive regulator is closed and live steam being admitted to the last named feeding device only when the locomotive reg- 140 ular is open.

2. An arrangement for supplying feed wa- 120 ter to locomotive boilers, comprising a hot water storage tank, a cold water tank, a dis- 125 tinct and separate feeding path leading re- 130 spectively from each of said tanks to the boiler, a feeding device which when supplied with live steam feeds the water from the hot 135 water storage tank over one of the said feed- 140 ing paths into the boiler, a second feeding device which when supplied with live steam feeds the water from the cold water tank over the second of said feeding paths into the 145 boiler, a live steam pipe connected with the 150 boiler and divided into two branches, one

of which leads to one of the said feeding devices and the other of which leads to the second feeding device, a device arranged at the bifurcation of the said live steam pipe, operated in dependence of the pressure within the valve chest of the engine, such pressure being in its turn dependent upon the position of the regulator of the locomotive, said device controlling the alternate admission of steam to said branches in such a manner that the passage through the first-named branch is opened when the locomotive regulator is closed while the passage through the last-named branch is opened when the locomotive regulator is opened.

3. An arrangement for supplying feed water to locomotive boilers as set forth in claim 2, wherein means are provided for controlling said branches and consist of a valve having two seats which are adapted to close or open the passage of steam through said branches alternatively.

4. An arrangement for supplying feed water to locomotive boilers as set forth in claim 1 with the additional feature that the means for discharging the feed water from the cold water tank to the boiler is in the form of an injector adapted to be operated by exhaust steam alone or by exhaust steam and live steam simultaneously.

5. An arrangement for supplying feed water to locomotive boilers comprising a closed hot water storage tank having its lowermost portion located above the highest water level of the boiler, a cold water tank, a distinct and separate feeding path leading respectively from each of said tanks to the boiler, an injector inserted into the feeding path from the cold water tank to the boiler, a live steam pipe connected with the boiler and divided into two branches, one of which leads to said hot water tank and the other of which leads to said injector, a member controlled by the pressure within the valve chest of the engine which depends upon the position of the locomotive regulator, opening the passage from the cold water tank to the injector when the locomotive regulator is opened, and a device arranged at the bifurcation of the said live steam pipe controlling the alternate admission of steam to the two branches and operated in dependence of the pressure within the valve chest of the engine and therefore in dependence of the position of the locomotive regulator, the passage to the live steam pipe through the first named branch being opened when the locomotive regulator is closed and the passage through the last named branch being opened when the locomotive regulator is open.

6. An arrangement for supplying feed water to locomotive boilers comprising a closed hot water storage tank having its lowermost portion located above the highest water level of the boiler, a cold water tank, a

distinct and separate feeding path leading respectively from each of said tanks to the boiler, an injector having an exhaust steam nozzle and a live steam nozzle and inserted into the feeding path leading from the cold water tank to the boiler, a pipe leading from the exhaust of the engine to the exhaust steam nozzle of the injector, a live steam pipe connected with the boiler and divided into two branches, one of which leads to said hot water tank and the other of which leads to the live steam nozzle of said injector, a device arranged at the bifurcation of the said live steam pipe controlling the alternate admission of the steam to said branches, operated

in dependence of the pressure within the valve chest of the engine, which in its turn is dependent from the position of the locomotive regulator, said device opening the passage through the first-named branch of the live steam pipe when the locomotive regulator is closed and opening the passage through the last-named branch only when the locomotive regulator is opened, a delivery water pipe leading from said injector, divided into two branches leading to the hot water tank and to the boiler respectively, a shut-off device arranged within the last-named branch and a second shut-off device arranged within the above mentioned live steam pipe leading from the boiler, both devices being interconnected in such a manner that whenever one of the two shut-off devices is closed the other is open and vice versa.

In testimony whereof I affix my signature.
